US00D929612S

(12) **United States Design Patent** (10) **Patent No.:** **US D929,612 S**
Styrc et al. (45) **Date of Patent:** **** Aug. 31, 2021**

(54) **CONNECTOR FOR MODULAR STRUCTURE**

(71) Applicant: **2724889 ONTARIO INC.**, Oakville (CA)

(72) Inventors: **Jacek Styrc**, Oakville (CA); **Sebastian Lysiak**, Bielsko-Biata (PL)

(73) Assignee: **2724889 ONTARIO INC.**, Oakville (CA)

(**) Term: **15 Years**

(21) Appl. No.: **29/723,176**

(22) Filed: **Feb. 5, 2020**

Related U.S. Application Data

(60) Division of application No. 29/635,278, filed on Jan. 30, 2018, now Pat. No. Des. 887,025, which is a continuation-in-part of application No. 15/815,973, filed on Nov. 17, 2017, now abandoned.
